BRACKET ROD MOUNTING

Anthony Vanderveld, Grand Rapids, Mich., assignor to Grand Rapids Store Equipment Company, Grand Rapids, Mich., a corporation of Michigan

Application February 14, 1949, Serial No. 76,322

6 Claims. (Cl. 248—251)

1

This invention relates to a mounting for horizontal rods, which in practice are carried on and extend between the outer and free end portions of suitable bracket supports, the rods being used generally in connection with store furniture for the placing thereon of garment hangers from which garments may be suspended, for display and ready access thereto and removal thereof from the supporting rods.

Such horizontal rods may be located in direct horizontal alignment adjacent the outer or open sides of display cabinets or cases, or located in front of and spaced from the vertical posts of supporting racks, forwardly extending bracket arms to carry the ends of the rods being permanently or adjustably mounted upon such supporting posts or upon equivalent means in cabinets to which the inner or rear ends of the brackets are connected. In other instances, particularly in modern design of store furniture in stores, the cases or cabinets or racks may not be located in direct alignment but successive cases disposed at varying angles, other than a straight angle, to each other. The garment holding rods paralleling the backs of the display cases or racks will likewise be successively located at substantially like angles to each other. The adjacent ends of two successive rods in practice are carried by the same forwardly extending bracket.

It is a primary object and purpose of the present invention to provide a fixture mounted on the outer end portion of a bracket which is capable of gripping the adjacent end portions of two of such garment hanging rods and securely holding them in any of the relative angular positions of one rod to the other that they may take. It is a further object and purpose to provide such fixtures or mounting for the rods which is of a practical, economically produced form, is readily adjusted to a desired position on the bracket arm so as to position garment hanger carrying rods when attached therewith at different distances from the back of a display case or rack to securely connect the mounting fixture at any selected position on the bracket arm, and for readily releasing a garment hanging rod when wanted, or for connecting one thereto.

It is a further object and purpose of the present invention to provide such mounting fixture whereby, with it and by using it, the garment hanging rods which generally are of an elongated tubular form require no special machining at or adjacent their ends but may be merely cut to length, and with a large tolerance with respect

2

to the length of a rod, or the lengths of different rods, thus reducing fabricating cost which has had to be met in previous installations of the rods.

An understanding of the invention for the accomplishment of the ends stated, and others not at this time enumerated, may be had from the following description, taken in connection with the accompanying drawing, in which,

Fig. 1 is an elevation, showing the rod mounting fixture connected at the outer end portion of a bracket arm, and illustrating a rod associated and connected therewith.

Fig. 2 is a plan view, showing two successive rods angularly disposed to each other and indicating positions thereof at extremes of angular movement.

Fig. 3 is a transverse vertical section substantially on the plane of line 3—3 of Fig. 4 looking in the direction indicated.

Fig. 4 is a fragmentary longitudinal vertical section, substantially on the plane of line 4—4 of Fig. 3, taken looking in the direction indicated.

Like reference characters refer to like parts in the different figures of the drawing.

The bracket arm 1, made generally from flat metal, may be of the detachable and adjustable type illustrated or, so far as the present invention is concerned, may be one which when once assembled in a display case or a rack support, will remain permanently in its assembled location.

At its outer end its upper and lower edges for a distance preferably are substantially parallel. It is with the outer end portion of the supporting bracket arm that two of the garment hanging rods 2 usually of a hollow tubular cylindrical form, are adapted to be operatively connected in any of the positions between an extreme position shown in full lines in Fig. 2, and an opposite extreme angular position indicated in dash lines. It is to be understood that all positions between the two extremes may be occupied by either of said rods, the half-way position between the two extremes placing the two rods substantially in longitudinal alignment.

The mounting fixture consists generally of two parts, each made of flat metal, one of which preferably will be the upper part of the fixture, though the fixture, shown in Fig. 1 may be reversed in position, including a generally horizontal upperside 3, from which a generally vertical downwardly extending extension 4 is bent, having a vertical slot 5 therethrough, greater in length than the vertical width of the outer end 55 of the bracket arm 1, and of a width for the

outer end portion of the arm 1 to pass freely therethrough. From the side edges of the upper side 3, spaced vertical sides 6 extend downwardly, each at its lower edge portion being formed with a concave recess 7, generally of arc shape but of a different and larger radius of curvature than the outside radius of curvature of the rod 2 which the mounting fixture is to carry. The sides 6 are of less length than the top 3, and at their inner or rear edges may be downwardly and forwardly inclined, as shown at 8, leaving a projecting section of the top 3 extending back thereof.

The lower member of the mounting fixture has a horizontal bottom 9 from which, at the front end, a section 10 is turned upwardly substantially at right angles, and has a vertical slot 11 therein substantially in height equal to the vertical height of the outer arm of the bracket 1 and of the same width as the previously described slot 5. At the inner or rear end of the bottom 9, a second section 12 is bent to extend upwardly at right angles, it having an aligned vertical slot 13 therein of the same width and of a slightly greater length than slot 11. At the upper end of the vertical section 10 a generally horizontal lip 14 is turned in a forward or outward direction.

From the side edges of the bottom 9, vertical sides 15 at right angles thereto extend upwardly. Each side 15 is formed with a downwardly cut or otherwise produced concave recess 16, the radius of curvature of which likewise is somewhat greater than the exterior radius of curvature of the rod 2. The edge portions of the sides 15 opposite the inclined edges 8 of the previously described sides 6 of the first mounting member are likewise inclined at generally the same angle of inclination as the angles at 8, as shown at 17.

The two members of the mounting fixture, in use are placed upon the outer free end portion of the bracket arm 1, said arm passing first through the slot 13, thence through the slot 11. The lower member is then held on the bracket arm 1, and may be moved thereon to any desired position. The upper member is then located over the lower member, arm 1 passing through slot 5. The sides 6 and 15 of the two members of the fixture occupy the same vertical planes. The upturned section 10 is immediately back of the downwardly extending section 4, and the horizontal terminal lip 14 is under the projecting or rear end portion of the top 3. Screws 18 pass through the top extension and are threaded through suitable openings made in the horizontal lip 14.

Before the screws are tightened to clamping position, the mounting fixture may be freely moved back and forth on the outer free end portion of the bracket arm on which it is placed, and the adjacent ends of the two garment hanger rods 2 inserted in the openings which are left in the sides by the upper and lower recesses at 7 and 16 in the lower and upper sides respectively of the sides 6 and 15 of the two members of the fixtures. On tightening the screws the sides 6 and 15, at or adjacent the bottoms of the recesses 7 and 16, bite into the tubular rods 2 at substantially opposite upper and lower portions thereof, such bite for all practical purposes, permanently securing the rods at their inserted ends against displacement. Nevertheless there is no interference with swinging movement of a rod or both of them to the different angular positions from one extreme to the other, and all others in between. The lower edge of the bracket arm 1 will

come against the metal of the section 4 at the lower end of the slot 5, the bottom 9 of the lower member will lie snugly against the under edge of the bracket arm 1, and the upper edge of the bracket arm 1 will be against the upper end of the slot 11. The mounting fixture is thus securely connected with the bracket arm, and held against accidental or other change of position, resisting all normal forces which would tend to cause a change in position.

It is evident that the hanger rods 2 may be cut as to length so as to bridge between a mounting fixture carried on one bracket arm and a second like fixture on a second bracket arm spaced therefrom, as for example when two of the bracket arms 1 are at opposite ends of a display case. The rods will be engaged and securely held even when roughly cut to length, as there is a large tolerance provided by the space between the sides 20 of a bracket arm 1 and the sides 6 and 15 of the mounting fixtures which parallel the arm. Therefore, a hanger rod is provided by merely cutting a length of the tubular material transversely across at a length which may vary according to a tolerance of a sixteenth or eighth of an inch, instead of thousandths of an inch.

The invention is of a practical, useful and successful and satisfactory character. The claims appended hereto define the invention which is to be considered comprehensive of all forms of structure coming within their scope.

I claim:

1. In a construction as described, a bracket arm, a rod mounting comprising, upper and lower members each slidably mounted on said bracket, said members having spaced sides at opposite sides of the bracket arm located in the same planes and having cooperative recesses in sides thereof providing two openings one at each side 35 of the bracket arm, each adapted to receive the end of a rod, part of said rod receiving recesses being in one member and part in the other, and manually operable means for drawing said members toward each other, to clamp at such recesses, against the rods and for securing said members against movement on said bracket arm.

2. In a structure as described, a bracket arm of flat metal located in a substantially vertical plane, a lower member mounted thereon having a bottom underneath the arm, an end section 50 extending upwardly at both ends of the bottom each having a slot therethrough through which the arm passes, and sides extending upwardly one at each side of the bottom, each of said sides 55 at its upper edge having a concave recess therein, a second member having a top, a downwardly extending section at the outer end thereof having a slot therethrough, through which the bracket arm passes, and sides extending downwardly one 60 at each edge of said top in the same plane as the sides of the lower member, each of said sides having inverted concave recesses over the recesses in the sides of the lower member, the inner end section of the lower member having a lip at its upper edge extending under the top of the upper member, and screws passing through said top and threading through said lip for drawing said lip and top together or releasing them for separation, whereby a rod may be gripped between the sides of the lower and upper members at the recessed portions at each side, and said members secured in fixed position on the bracket arm on tightening said screws.

3. A structure as defined in claim 2, said re-

cessed portions each having a radius of curvature greater than the exterior radius of curvature of a rod to be received therein, whereby said a rod may be adjusted to different angular positions with respect to the bracket arm and held against disconnection in such positions.

4. In a structure of the class described, a bracket arm, a fixture slidably mounted on said bracket arm having sides parallel to the bracket arm and spaced outwardly therefrom one at each side of the arm, said fixture having passages therethrough at its ends for the arm to slidably extend through the passages, and said sides of the fixture having rod receiving recesses for the entrance of one end of a rod therein, and manually operable means for simultaneously clamping said fixture to a rod or rods inserted through the recesses of either one or both of said sides, and for securing the fixture to the bracket arm against movement relative thereto.

5. In a structure as described, a bracket arm, a fixture thereon comprising, upper and lower parts, each of said parts of said fixture having openings for slidable passing of the arm therethrough, said parts of said fixture providing vertical sides, one at each side of the bracket arm and spaced therefrom, each of said sides having a rod receiving opening therein, and means for adjustably connecting said parts of the fixture

together, said means being adapted for manual operation for releasably securing the fixture against movement on said arm and for decreasing the size of said rod receiving openings, to thereby grip a rod, having an end portion entered into an opening, at substantially diametrically opposed upper and lower sides thereof.

5 6. A structure as defined in claim 5, said parts of the fixture being mounted on the bracket arm one over the other and said manually operable means for releasably securing the fixture to the bracket arm and clamping rods at the ends thereof at the sides of the fixture comprising, screws adjustably connecting said parts of the fixture at the inner portions thereof.
